(57) **CLAIM**

The ornamental design for an electronic pipette, as shown and described.

DESCRIPTION

FIG. 1 is a left perspective view of the electronic pipette illustrating the new design;

FIG. 2 is a right side view thereof;

FIG. 3 is a rear perspective view thereof;

FIG. 4 is a rear view thereof;

FIG. 5 is an enlarged top view thereof; and,

FIG. 6 is an enlarged bottom view thereof.

The closely spaced diagonal lines in FIGS. 1, 2, 4 and 5 views represent surface ornamentation.
